UNITED STATES PATENT OFFICE.

EVERT ASCHE, OF CLARA CITY, MINNESOTA.

RATCHET-BRACE.

1,328,111.

Specification of Letters Patent. Patented Jan. 13, 1920.

Application filed June 27, 1918. Serial No. 242,238.

To all whom it may concern:

Be it known that I, EVERETT ASCHE, a citizen of the United States, and a resident of Clara City, in the county of Chippewa and 5 State of Minnesota, have invented a new and Improved Ratchet-Brace, of which the following is a full, clear, and exact description.

This invention relates to braces or brackets and has for an object the provision of an 10 improved construction which may be used as a clamping brace or bracket and also as a drill brace.

Another object in view is the provision 15 of an improved arrangement of brace which may be adjusted in length.

A further object of the invention is the provision of a brace with an adjustable resting member adapted to face in a plurality of different directions so as to coact 20 with objects in different places in respect to the drill carried by the opposite end of the bracket.

A further object of the invention is the provision of a bracket having a foot at one 25 end and a drilling contrivance at the opposite end arranged to move the drill toward the end carrying the foot or in an opposite direction.

In the accompanying drawing:

30 Figure 1 is a side view of a device embodying the invention.

Fig. 2 is a section through Fig. 1 on line 2—2.

Fig. 3 is a transverse sectional view 35 through Fig. 1 on line 3—3.

Fig. 4 is a transverse sectional view through Fig. 1 on line 4—4.

Fig. 5 is a fragmentary sectional view 40 through Fig. 1 on line 5—5.

Fig. 6 is a transverse horizontal sectional view through Fig. 2 on line 6—6.

Referring to the accompanying drawing by numerals, 1 indicates a bar telescopically fitting into a tubular sleeve 2 which sleeve is 45 bent for producing a hollow arm 3 at the lower end, while the hollow bar 1 is bent for producing a supporting arm 4 at the upper end. Arm 3 is provided with one or more projections 5 fitting into notches 6 on 50 the fitting 7, which fitting has a supporting member 8 slidably fitting into arm 3, and a base 9 adapted to engage an article or engage the shoulder when the device is in use according to the particular position thereof.

55 When it is desired to clamp an article or bore a hole therethrough the parts are ar-

ranged as shown in Fig. 1, but in case it is desired to bore a hole through an object not capable of being positioned between the arms 3 and 4 the base 9 is turned over to the 60 dotted position shown in Fig. 1 and the wheel 10 and all parts carried thereby are turned over so that the drill 11 will be pointed in the opposite direction. The sleeve 2 is provided with a number of apertures 12 for receiving the end of locking pin 13, said locking pin fitting into any of the apertures 12 according to the position of the bar 1 which carries the locking pin. This locking pin is shown in detail in Fig. 6 and 70 consists of an ordinary round pin pressed by a spring 14, which spring and pin are locked in a bore 15 in bar 1. When it is desired to change the position of the bar 1 pin 13 is depressed until the sleeve 2 can be 75 rotated a short distance whereupon the pin 13 will be out of register and the bar 1 may be moved to any desired position and the parts turned back so that the pin will register with some of the apertures 12 into which it 80 will snap when brought into said register. An aperture 16 is also provided at right angles to aperture 12 whereby the arm 3 and associate parts may be held at right angles to arm 4. This is desirable under 85 some circumstances, as for instance where the standards or other bracing support is located out of line with the plates to be drilled.

The fitting 10 is a T-shaped fitting and is 90 threaded on to arm 4 so as to rotate around said arm or rather swung to two opposite extreme positions, namely to the position shown in Fig. 1 and the position diametrically opposite. In order to lock the fitting 95 when it is in either position a spring 17 is provided having a bend fitting into the bore 18 of body 19 for fitting into the notch 20 when the fitting is in the position shown in Fig. 1 and into notch 21 when in the opposite 100 position. A groove 22 is provided to accommodate the body 19 when depressed so that the fitting 7 may rotate and when moved for a half revolution a spring is released and is allowed to snap into the opposite slot. 105 The fitting is internally threaded as shown in Fig. 2 for accommodating the externally threaded sleeve 23, which sleeve is provided with an operating member 24, which is preferably in the shape of a disk so that it may 110 be readily moved at any point. The sleeve 23 acts against the shoulders 25 of the tool

receiving socket 26, whereby when the sleeve is rotated in one direction the socket is forced downwardly or toward the arm 3, and when moved in the opposite direction 5 the socket is moved away from arm 3. This presents a feed for the drill so that it may be fed as fast or slow as desired. A ratchet wheel 27 is rigidly secured to the upper end of the shaft 28 which carries the socket 26, 10 the connecting means being threads, key or any other desirable means. A crank arm 29 is loosely mounted on the rod 28 and a bracing arm 30 is also loosely mounted on rod 28. The arms are raised as shown in 15 Fig. 1 so as to straddle the ratchet wheel 27 whereby the tool 31 pivotally mounted on these arms may be continually maintained in contact with the ratchet by a spring 32 so that as the knob 33 is moved back and forth and arm 29 is moved back and forth the rod 28 and socket 26 and whatever is connected with said socket will be rotated by an intermittent motion. It is, of course, understood that if arm 29 is rotated 20 continuously the parts connected therewith will also be rotated continuously.

What I claim is:

1. A bracket of the character described comprising a substantially U-shaped body 30 formed with a foot at one end, a rotatable fitting at the opposite end and in alignment with said foot, means for locking said fitting in a plurality of adjusted positions, a tool receiving member having a shank or rod 35 extending through the fitting, means for rotating said rod, and an adjusting member threaded into the fitting, said adjusting member having an annular flange whereby same may be moved at any point around the 40 fitting for adjusting said tool receiving member toward and from said foot.

2. A bracket of the character described comprising a body adjustable longitudinally provided with an arm at each end, a foot 45 arranged on one of said arms, a fitting arranged on the other arm and formed so as to rotate around the arm, a catch mounted on the last mentioned arm for locking the fitting in any of its adjusted positions, a tool 50 receiving socket formed with a rod extending through said fitting, an adjusting member connected with the fitting and acting on said socket for moving the tool carried thereby toward and from said foot, and a power 55 member connected with said rod for rotating the same.

3. A brace of the character described comprising a body substantially U-shaped with the parts connecting the two legs of the U 60 telescopically fitting one into the other, means for locking said telescoping section in a plurality of adjusted positions, a fitting at the end of each of said legs one of said fittings acting as a foot and the other as a tool 65 receiving member, both of said fittings being

adjustable so as to act in either of two directions, a rotatable tool receiving member arranged in the tool receiving member, and means for operating said tool receiving member.

4. In a ratchet brace, in combination a body having spaced opposite arms, said body consisting of two relatively adjustable parts, a tool carrier mounted upon one of said arms and movably carried thereon whereby it can be disposed inwardly or outwardly with respect to said arms, and a base rotatably mounted upon the other of said arms whereby it can be disposed inwardly or outwardly with respect to said arms.

5. In a ratchet brace, in combination a body having spaced opposite arms, said body consisting of two relatively adjustable parts, a tool carrier mounted upon one of said arms and movably carried thereon whereby it can be disposed inwardly or outwardly with respect to said arms, means for securing said tool carrier in a plurality of positions, a base rotatably mounted upon the other of said arms whereby it can be disposed inwardly or outwardly with respect to said arms, and means for securing said base in a plurality of positions.

6. In a ratchet brace, in combination a body having spaced opposite arms, said body 95 consisting of two relatively adjustable parts, means for locking together said parts of the body in different positions of adjustment, a tool carrier rotatably mounted upon one of said arms and movably carried thereon, 100 whereby it can be disposed inwardly or outwardly with respect to said arms, and a brace rotatably mounted upon the other of said arms whereby it can be disposed inwardly or outwardly with respect to said 105 arms.

7. In a ratchet brace the combination of a body substantially U-shape and having two parts telescopically associated, means for locking the telescoping parts together, a 110 base rotatably carried by one of the legs of said body, means for locking the base in a position nearest the opposite leg of said body and in one substantially diametrically opposite, a sleeve rotatably carried by the other 115 leg of said body, a tool carrying member rotatably mounted on said sleeve, a latch arranged to lock the sleeve so that said tool member is nearest the opposite leg of said body or in an opposite position, means for rotating said tool member about its axis, and a means for forcing said tool member away from or toward the base.

8. In a ratchet brace, the combination of a body substantially U-shaped with the parts 125 connecting the two legs of the U telescopically fitting one into the other, a plurality of apertures in the outer telescoping member of said body, a spring actuated locking pin slidably mounted in the inner telescopic 130

ing member of said body so as to engage any one of said apertures and so lock the two members together, a base, a support fixed to said base rotatably carried by one of the 5 legs of said body so that said base may be turned toward or away from the opposite arm of said body, means for locking the base

in the two said positions, a tool carrying member rotatably carried on the other arm of said body, means for rotating said tool member about its axis, and means for forcing said tool member away from or toward the base.

EVERT ASCHE.
